Primary Examiner — Mehri F Bajoul*(74) Attorney, Agent, or Firm* — Justin Lampel(57) **CLAIM**

The ornamental design for a roundnet game, as shown and described.

DESCRIPTION

FIG. 1 is a perspective view of a roundnet game showing my new design;

FIG. 2 is a perspective view of the roundnet game without the broken line net, for complete disclosure;

FIG. 3 is a side elevational view of the roundnet game thereof;

FIG. 4 is a front elevational view of the roundnet game thereof;

FIG. 5 is a top plan view of the roundnet game thereof; and, FIG. 6 is a bottom plan view of the roundnet game thereof. The even length broken lines in FIG. 1 illustrate portions of roundnet game that forms no part of the claim design. The dash-dot lines on the underside of the leg portions depict the boundaries and form no part of the claimed design.
